United States Patent Office

Des. 186,786
Patented Dec. 1, 1959

186,786

LUMINAIRE

Myron F. Pettengill and Charles H. Rex, Hendersonville,
N.C., assignors to General Electric Company, a cor-
poration of New York

Application June 26, 1958, Serial No. 51,566

Term of patent 14 years

(Cl. D48—31)

Fig. 1

Fig. 2

Fig. 3.

Figure 1 is a side elevational view of a luminaire showing our new design;

Figure 2 is a perspective view thereof as seen from the top right of Figure 1; and

Figure 3 is a top plan view thereof with the sleeve omitted for convenience of illustration.

The dominant features of our new design are shown in solid lines and stippling in the drawings.

We claim:

The ornamental design for a luminaire, as shown and described.
